UNITED STATES PATENT OFFICE.

JAN SMOTER, OF CONEMAUGH, PENNSYLVANIA, ASSIGNOR OF ONE-FOURTH TO
ADALBERT RYS, OF CONEMAUGH, PENNSYLVANIA.

BURGLAR-ALARM.

1,193,306.

Specification of Letters Patent.

Patented Aug. 1, 1916.

Application filed September 9, 1915. Serial No. 49,704.

To all whom it may concern:

Be it known that I, JAN SMOTER, a subject of the Emperor of Austria-Hungary, residing at Conemaugh, in the county of Cambria 5 and State of Pennsylvania, have invented certain new and useful Improvements in Burglar-Alarms, of which the following is a specification.

This invention relates to certain new and 10 useful improvements in burglar alarms.

The primary object of the invention is the provision of an automatic window-operated audible alarm, whereby the persons in the vicinity of the window will be advised whenever the window is actuated in the opening 15 operation.

A further object is to provide actuating mechanism for an alarm clock whereby the alarm thereof will be set in motion in the 20 event of an opening of a window by any person, such as a burglar attempting to gain entrance therethrough.

A still further object is to provide an actuating means for the controlling shaft of an 25 alarm clock so associated with a window as to be automatically operated during the opening operation but unaffected thereby during the closing of the window.

With these general objects in view and 30 others that will appear as the nature of the invention is better understood, the same consists in the novel construction, combination and arrangement of parts hereinafter more fully described, illustrated in the accompanying drawings, and then claimed.

In the drawings forming a part of this application and in which like designating characters refer to corresponding parts throughout the several views:—Figure 1 is 40 a front elevation of the device illustrated in connection with a window, and parts being broken away. Fig. 2 is a horizontal sectional view thereof. Fig. 3 is an enlarged detail sectional view taken upon line III—III of 45 Fig. 2. Fig. 4 is a similar view upon line IV—IV of Fig. 2, and, Fig. 5 is a similar view upon line V—V of Fig. 1.

Referring more in detail to the drawings, the present device may be employed in connection with either the upper or lower sliding sash of any ordinary window and is herewith illustrated in connection with the lower sash 10 slidably mounted in the window casing 11, the side of the wall which is

provided with such window being shown at 55 12, it being understood that the side of the window is illustrated which is within the room or building.

A casing 13 is secured by brackets 14 to the wall 12 and is provided with an alarm clock 60 15 removably positioned therein and retained by means of slotted feet 16 carried by the clock and adapted to be removably positioned upon supporting screws 17 arranged interiorly of the casing 13. 65

A toothed rack 18 is rigidly secured to the edge 19 of the sash 10 and is in constant mesh with a pinion 20 fixed upon a shaft 21 journaled in a socket 22 provided in the adjacent face of the window casing 11. The 70 said shaft 21 projects forwardly of the casing 11 and is arranged in a plane perpendicular to the sash 10 and is provided upon its projecting end with a beveled gear 23. A bracket 24 is carried by the window casing 11 and has an axle 25 journaled therein, the said axle being provided with a beveled gear 26 at one end thereof in constant mesh 75 with the afore-mentioned similar gear 23. The opposite end of the axle 25 is provided 80 with a clutch head 27 having inclined toothed faces 28 forming clutch members.

It being understood that the alarm clock 15 may be of any well-known form and provided with the usual alarm bells 29, and 85 with the usual setting shaft 30, the present invention provides a pinion 31 fixed upon the outer free end of the said setting shaft 30. An idle pinion 32 is mounted upon a bracket 33 within the casing 13 and is 90 adapted to mesh with the afore-mentioned pinion 31 when the alarm clock is operatively positioned within the casing 13. A boss 34 is provided through the rear of the said casing and has a shaft 35 journaled 95 therein, the inner end of which shaft has a pinion 36 secured thereto in constant mesh with the afore-mentioned pinion 32 while a similar pinion 37 is fixed upon the outer end of the said shaft 35. 100

A connecting rod 38 is journaled in a bracket 39 carried by the wall 12 and a bracket 40 carried by the casing 11 and is provided at one end with a pinion 41 in constant mesh with the aforementioned clock 105 pinion 37. The opposite end of the rod 38 is provided with a squared portion 42 upon which a coöperating clutch disk 43 is slid-

ably mounted and is normally held in resili-
ent engagement with the clutch teeth 28 of
the head 27 by means of an expansion spring
44 interposed between the clutch disk 43 and
5 the bracket 40 and encircling the said rod 38.

From this detailed description of the de-
vice, the complete operation thereof will be
apparent.

The alarm clock 15 having the usual alarm
10 mechanism thereof wound up and set so as
to operate at any desired time, the clock is
then positioned within the casing 13, with
the pinion 31 of the said shaft 30 of the
alarm in mesh with the adjacent pinion 32
15 whereby the said set shaft is operatively
connected to the rod 38 by means of the pin-
ions 36, 37 and 41 and the said shaft 35.
The raising of the window sash 10 results in
rotating the shaft 21 through the agency
20 of the gear 20 and the sash rack 18, such
operation resulting in turning the gear 23
and the gear 26 so that the rod 38 is revolved
as the clutch members 27 and 43 are in their
normal operative positions. Such revolving
25 of the rod 38 turns the setting shaft 30 of
the alarm mechanism and as soon as the
shaft positions the mechanism at the pre-
determined time at which the alarm was de-
sired to operate the alarm being then re-
30 leased will be sounded, giving an audible sig-
nal which denotes that the sash has been
opened. The rod 38 is not affected by the
lowering of the sash 10 as the clutch disk 43
will ratchet over the teeth 28 of the disk
35 head 27 when the axle 25 is reversely re-
volved during the sash closing operation, it
being seen that the adjacent end 45 of the
rod 38 is freely journaled within a central
bore 46 of the axle 25 and that during this
40 ratcheting operation, the disk 43 slides upon
the squared portion 42 of the rod without
being revolved by the said clutch head 27.
A serviceable burglar alarm for a window
sash is thus provided which will advise the
45 occupants of a house of any opening of the
window sash while the clock employed for
giving the alarm is not interrupted in its use
as a time-piece in the house-hold.

While the form of the invention herein
50 shown and described is what is believed to
be the preferred embodiment thereof, it is
nevertheless to be understood that various
forms, modifications and arrangements of
the parts may be made without departing
55 from the spirit and scope of the invention
as claimed.

What I claim as new is:—

1. A burglar alarm comprising in combi-
nation with a shiftable window sash, a shaft
journaled adjacent said sash, an alarm clock 60
positioned adjacent said sash, a removable
rod operatively connected at one end to the
setting mechanism of the alarm of the clock,
and operative connections between the oppo-
site end of the said rod and the said shaft 65
operable only during the opening of the win-
dow.

2. A burglar alarm comprising in combi-
nation with a sliding sash and an alarm
clock having a setting shaft for the alarm 70
thereof, a rod revolvably-mounted and de-
tachably operably connected with the said
setting shaft, and releasable operative con-
nections between the opposite end of the said
rod and the said sash. 75

3. A burglar alarm comprising in combi-
nation with a sliding sash and an alarm
clock having a setting shaft for the alarm
thereof, a rod revolvably-mounted and de-
tachably operably connected with the said 80
setting shaft, a stub-shaft journaled adjac-
ent the said sash, rack and gear connections
between the said stub-shaft and sash, a
clutch head operatively connected to said
stub-shaft, and automatically releasable 85
clutching means between the said rod and
head in operative engagement during the
opening of the sash.

4. A burglar alarm comprising in combi-
nation with a sliding sash of a window, a 90
casing having an open front and secured
adjacent the said sash, an alarm clock re-
movably positioned within the said casing
and having a setting shaft for the alarm
mechanism thereof, an axle journaled adjac- 95
ent the said sash, operative connections be-
tween the said axle and sash, a clutch head
at one end of the said axle having inclined
teeth thereon, the said head and axle having
a central longitudinal bore therein, a 100
bracket secured adjacent said head, a rod
journaled in the said bracket and bore and
having a squared portion adjacent the said
head, operative connections between the op-
posite end of the said rod and the said set-
ting shaft, a clutch disk slidably-mounted
105 upon the said squared portion adjacent the
said head teeth, and an expansion spring be-
tween the said disk and bracket.

In testimony whereof I affix my signature. 110

JAN SMOTER.
